[57] CLAIM

The ornamental design for a grip for a hammer tacker, as shown and described.

DESCRIPTION

FIG. 1 is a right side elevational view of a grip for a hammer tacker showing my new design;

FIG. 2 is a left side elevational view thereof;

FIG. 3 is a top plan view thereof;

FIG. 4 is a bottom plan view thereof;

FIG. 5 is a rear elevational view thereof; and

FIG. 6 is a front elevational view thereof.

The broken line portions of the drawing are for illustrative purposes only and form no part of the claimed design.

FIG. 3FIG. 5FIG. 6FIG. 4
